TRUCK

David M. Light, Chicago, Ill., assignor to American Steel Foundries, Chicago, Ill., a corporation of New Jersey

Application October 11, 1941, Serial No. 414,550

34 Claims. (Cl. 105—197)

My invention relates to a railway car truck and more particularly to a four wheel railway car truck utilizing a novel spring suspension comprising friction elements in engagement with the columns of the frame and with the ends of a spring cap mounted on a bolster supporting auxiliary spring.

The general object of my invention is to devise a novel form of railway freight car truck of the above type suitable for high speed freight car service and adapted to development of varying amounts of friction as may be required under different operating conditions.

A specific object of my invention is to devise a high speed quick wheel change type of freight car truck utilizing truss side frames with central bolster openings in which the ends of the load carrying member or bolster may be spring supported, the bottom wall of the bolster being interlocked with a novel form of friction shoe having frictional engagement with the adjacent column, said shoe also having frictional engagement with a spring cap with which the bolster is also interlocked.

In my novel arrangement, the truck comprises a side frame having a two-level tension member, the upper level affording a seat for a plurality of long travel coil springs, said upper level being cut away centrally of the frame to afford an opening for a somewhat longer bolster supporting coil spring, said spring supporting on the top thereof a spring cap comprising V-shaped friction surfaces at the ends thereof in frictional engagement with complementary surfaces on friction shoes abutting respective columns of the frame.

My novel arrangement contemplates a structure such as that above described wherein the bolster is engaged by means of a spring plate with a novel follower which interlocks the bolster with the above-mentioned spring cap as well as with the above-mentioned friction shoes.

In the drawings

Figure 1 is a fragmentary sectional view of a railway car truck embodying my invention, the section being taken in a plane bisecting one of the frame members longitudinally and as indicated by the line 1—1 of Figure 2, only one end of the truck being shown inasmuch as it is similar at opposite ends.

Figure 2 is a fragmentary sectional view of the truck structure shown in Figure 1, the section being taken in the horizontal plane indicated by the line 2—2 of Figure 1.

Figure 3 is a sectional view of the truck ar-

rangement shown in Figures 1 and 2, the section being taken substantially in the transverse vertical plane bisecting the truck frame and as indicated by the line 3—3 of Figure 1.

Describing the structure in detail, my novel truck comprises a truss side frame having the usual outline with the compression member 2, the tension member 4, and integrally formed columns 6, 6 merging therewith and forming the central bolster opening 8 and the adjacent window opening 10. Above the bolster opening 8, the compression member may be of box-section as best seen at 12 in the sectional view of Figure 3 and below the bolster opening the tension member 15 may have a box-section with a bottom chord 14, a top chord 16, inboard and outboard side walls 18 and 20, and spaced vertical transverse reinforcing ribs 22, 22, said top chord being widened beneath said bolster opening to form a main spring seat 24 for coil springs seated thereon, said coil springs being diagrammatically indicated as at 32, 32 and being symmetrically seated on the seat 24 as may best be understood from a consideration of the top plan view of Figure 2. Positioning means 30, 30 may be formed on the seat 24 for the springs 32, 32 and an annular flange 34 may be formed on the web 16 around the opening 36 therein, said flange being reinforced by the vertical ribs 23, 23. Centrally of the spring seat 24, the top chord 16 is interrupted to form the before-mentioned opening 36 for reception of the auxiliary spring 38, said spring being afforded a seat as at 39 on the bottom web 14 of the tension member. The upper end 35 of the spring 38 is positioned against a spring cap 42 as hereinafter described, and the upper ends of the spring group 32 may be confined in well known manner by a spring plate 40 upon which the end of the bolster may seat in interlocking engagement therewith as at 41, 47.

The spring cap 42 comprises the arcuate inboard and outboard side walls 44 and 46 respectively, merging at the ends thereof with the V-shaped diagonal friction surfaces formed at the ends of the cap and in complementary engagement with the friction shoes 72, 72 as at 82, 82. The cap also comprises a top wall 50 with an annular opening 52 centrally thereof, said top wall being downwardly flanged as at 54 around said opening to provide a spring seat between the flanged portion and the arcuate walls 44 and 46 for the spring 38 as at 56 in the manner above described.

Positioned in the opening 52 is the depending hollow lug 70 formed on the follower 58, said

follower 58 being of rectangular plate-like form as viewed in Figure 2 with a relatively thick and narrow shoe engaging portion 62 at each end thereof recessed as at 64 in the top of the associated friction shoe in a manner hereinafter described. Atop each narrow portion is a recess 66 receiving the positioning lug 41 on the bottom of the spring plate 40. Centrally of the follower 58 is an opening 68 aligned with and slightly smaller than the opening 52 in the spring cap 42. The opening 68 in the follower is partly defined by the wall of an annular hollow lug 70 which projects downwardly into the opening 52 in the spring cap as heretofore described, thus positioning the follower 58 with respect to the spring cap. Extending into the top of the opening 68 is a lug 43 formed on the bottom of the spring plate 40. Thus, it may be seen that the spring plate 40 is positioned with respect to the follower by means of the spaced lugs 41, 43 and 48.

Each friction shoe 72 is a generally rectangular compact body of metal comprising a bottom wall 74, spaced side walls 76, 76 and a rear wall 78 on the outer side of which is formed a friction surface in frictional engagement as at 80 with the abutting friction surface 7 on the adjacent column, said last-mentioned surface being machined on the column or welded thereto as at 9, 9. On the inner side of each shoe is formed a V-shaped friction surface in complementary engagement as at 82 with the abutting end of the spring cap 42, and a pocket 83 is formed at the bottom of each shoe by said V-shaped surface, said side walls and said bottom wall, within which pocket is positioned the associated end of the spring cap. In the top of each shoe is formed a recess 85 within which is received the associated end 62 of the spring cap 42, as heretofore described.

The bolster 86 is of generally rectangular box-like form and comprises the side walls 88, 88, the intermediate transverse vertical wall 90 parallel with said side walls, the top wall 92, and the bottom wall 94. Each side wall of the bolster is provided with a vertical positioning lug 96 for interlocking engagement with a bracket 98 formed on the inboard web of the column 6. The depth of the lug 96 is less than the distance between the top of the bracket 98 and the top of the bolster opening 8 as indicated at A in Figure 3 so that the bolster may be raised in the bolster opening and removed therefrom while the supporting spring group and novel friction device remain in normal assembled relationship.

In assembling my novel truck, it will be apparent that the spring group 32 and spring 38 may be positioned on the tension member on their respective seats, after which the novel friction shoes may be positioned against the columns, the spring cap 42 may be placed upon the spring 38 and interlocked with said shoes by the follower 58, and the bolster may be inserted at the top of the bolster opening and may be positioned with respect to the follower 58 as above-described.

It will thus be apparent that I have designed a quick wheel change railway car truck wherein the lower web of a two level tension member affords a spring seat centrally thereof for a spring auxiliary to the normal bolster supporting spring group, said spring supporting a spring cap with V-shaped friction surfaces at the ends thereof in engagement with complementary surfaces on associated friction shoes, said shoes also having frictional engagement with the adjacent columns

and wherein the bolster is interlocked with said shoes and said spring cap by a follower and with the inboard webs of the adjacent columns by guide lugs. It will also be apparent that by varying the resiliency of the auxiliary spring, varying amounts of friction may be developed, as desired.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

15 I claim:

1. In a railway car truck, a side frame comprising tension and compression members and spaced columns defining therewith a bolster opening and spaced window openings, said tension member comprising top and bottom webs, said top web having an annular opening therein, a spring group seated on said top web, an auxiliary spring extending through said last-mentioned opening and seated on said bottom web, a spring cap seated on said auxiliary spring and comprising a plurality of V-shaped friction surfaces, friction shoes in frictional engagement with respective surfaces and with respective columns, a follower interlocked with said shoes and said cap, and a bolster extending into said bolster opening, supported by said spring group, and interlocked with said follower.

2. In a railway car truck, a truss side frame comprising spaced columns partly defining therebetween a bolster opening, wear plates mounted on said columns, a plurality of friction shoes each comprising a friction surface in abutment with the adjacent wear plate and a friction face on the opposite side thereof, bolster supporting springs mounted on said frame, a spring cap seated on certain of said springs and comprising friction surfaces in engagement with said faces, a member seated on and engaged with said shoes and engaged with said cap, a spring plate seated on other of said springs and engaged with said member, and a bolster end received in said opening, seated on said plate, and engaged therewith.

3. In a railway car truck, a truss side frame comprising spaced columns partly defining therebetween a bolster opening, a plurality of friction shoes in frictional engagement with said columns, each of said shoes comprising a V-shaped friction face, bolster supporting springs mounted on said frame in said opening, a spring cap seated on certain of said springs and comprising friction surfaces complementary to and in engagement with said faces, a member seated on and interlocked with said shoes and interlocked with said cap, a spring plate seated on other of said springs and interlocked with said member, and a bolster received in said opening, seated on said plate, and interlocked therewith.

4. In a railway car truck, a side frame comprising a bolster opening and spaced columns, a pair of friction shoes each comprising an outer flat face frictionally abutting one of said columns, and an inner V-shaped face, bolster supporting springs seated on said frame in said opening, a spring cap on one of said springs and comprising V-shaped friction surfaces in complementary engagement with the V-shaped faces on said shoes, a follower engaged with said cap and both of said shoes, and a bolster extending into said opening,

supported by other of said springs and engaged with said follower.

5. In a railway car truck, a truss side frame comprising top and bottom members and spaced columns defining therewith a bolster opening, said bottom member comprising top and bottom webs, an opening in said top web, a plurality of coil springs seated on said top web, a relatively long coil spring as compared with said other coil springs extending through said opening and seated on said bottom web, a spring cap positioned on said last-mentioned spring and comprising friction faces, friction shoes in frictional engagement with respective faces and respective columns, and follower means seated on said shoes and engaged with said cap, said first-mentioned springs affording bolster supporting means.

6. In a railway car truck, spaced side frames each comprising a compression member, a two-level tension member, and spaced columns defining therewith a bolster opening, a plurality of resilient means seated respectively on the upper and lower levels of said tension member, a spring cap seated on the intermediate of said resilient means and comprising friction faces, shoes in frictional engagement with said faces and said columns, and a bolster having an end extending into said opening, said end being supported on and interlocked with said shoes and interlocked with said cap, and said end being additionally supported by other of said resilient means.

7. In a railway car truck, a side frame comprising a bolster opening and spaced columns, wear plates mounted on said columns, a plurality of friction shoes each comprising an outer flat face frictionally abutting one of said wear plates and an inner V-shaped friction face, bolster supporting springs seated on said frame in said opening, a spring cap seated on certain of said springs and comprising V-shaped friction surfaces in complementary engagement with respective of said V-shaped friction faces, and a bolster extending into said opening, supported on other of said springs, and said shoes, said bolster being vertically movable with respect to said cap but being interlocked therewith against relative movement longitudinally and transversely of said frame.

8. In a railway car truck, a side frame comprising a compression member, a two-level tension member and spaced columns defining therewith a bolster opening, a plurality of coil springs seated respectively on the upper and lower levels of said tension member, a spring cap supported by certain of said springs and comprising friction faces, friction shoes in frictional engagement with respective faces and respective columns, a follower engaged with said cap and said shoes, and a bolster extending into said opening, supported by other of said springs, and interlocked with said follower.

9. In a railway car truck, a side frame comprising a compression member, a two-level tension member and spaced columns defining therewith a bolster opening, wear plates mounted on said columns, a plurality of coil springs seated respectively on the upper and lower levels of said tension member, a spring cap supported by the intermediate of said springs and comprising friction faces, friction shoes in frictional engagement with respective faces and respective plates, and a bolster extending into said opening supported by other of said springs and said shoes, said bolster being interlocked with said cap against relative longitudinal or transverse movement with respect thereto.

10. In a railway car truck, a side frame comprising top and bottom members and spaced columns defining therewith a bolster opening, a plurality of springs supported on said bottom member in said opening, a bolster supported on certain of said springs, a spring cap seated on other of said springs and comprising V-shaped friction faces at the ends thereof and an opening in the top wall thereof, friction shoes in frictional engagement with respective faces and respective columns, and a member interlocked with said shoes and said bolster and comprising engaging means extending into said last-mentioned opening.

11. In a follower for a railway car truck, a flat member having a narrowed shoe engaging portion at each end thereof and interlocking means on the top thereof, and a depending lug centrally of said member and intermediate said portions for interlocking engagement with an associated friction means.

12. In a railway car truck, a side frame comprising a compression member, a tension member, and spaced columns defining therewith a bolster opening, a plurality of coil springs seated on said tension member, a spring cap supported by certain of said springs and comprising friction surfaces, friction shoes in frictional engagement with respective surfaces and respective columns, a follower engaged with said cap and said shoes, and a bolster extending into said opening, supported by other of said springs, and engaged with said follower.

13. In a railway car truck, a truss side frame comprising a compression member, a tension member, and spaced columns defining therewith a bolster opening, a plurality of springs seated on said tension member, a spring cap on certain of said springs, friction shoes supported by said cap below the tops of the other of said springs and in frictional engagement with respective columns, a member interlocking said shoes and said cap, and a bolster end received in said opening, supported on the last-mentioned springs, and interlocked with said last-mentioned member.

14. In a railway car truck, a side frame comprising top and bottom members and spaced columns defining therewith a bolster opening, a plurality of coil springs supported on said bottom member in said opening, a spring cap seated on certain of said springs and comprising V-shaped friction surfaces at the ends thereof and an opening in the top wall thereof, friction shoes supported by said columns in frictional engagement with said surfaces, a member interlocked with said shoes and comprising positioning means extending into said last-mentioned opening, and a bolster supported on the other of said springs at a point above said cap and engaged with said member.

15. In a railway car truck, a frame comprising spaced columns and an intervening bolster opening, friction means comprising friction shoes in frictional engagement with respective columns, and wedge means resiliently supported between said shoes in wedge engagement therewith, a bolster in said opening comprising a bottom wall bearing vertically on said shoes for actuation thereof, and a spring group on said frame bearing against said bottom wall for support of said bolster.

16. In a railway car truck, a side frame comprising a bolster opening and spaced columns, bolster supporting resilient means supported by said frame in said opening, a spring cap support-

ed by certain of said means, a plurality of friction shoes each having frictional engagement with said cap and with the adjacent column, a follower seated on said shoes and interlocked therewith and with said spring cap, and a bolster extending into said opening, supported by said means, and bearing on said follower.

17. In a side frame for a railway car truck, top and bottom members and spaced columns defining therewith a bolster opening, a plurality of bolster supporting springs on said bottom member in said opening, friction means on the intermediate of said springs, friction elements engaged with said means and respective columns, and follower means seated upon and interlocked with 15 said elements.

18. In a railway car truck, a side frame comprising a bolster opening and spaced columns, friction surfaces on said columns, resilient means seated on said frame in said opening, a cap on certain of said means and comprising V-shaped friction faces, friction shoes in frictional engagement with said faces and said surfaces, and a bolster extending into said opening and supported on other of said resilient means, said bolster being 20 25 operatively engaged with said shoes.

19. In a railway car truck, a side frame comprising spaced columns and an intervening bolster opening, a spring group on said frame in said opening, a wedge member resiliently supported 30 from said frame in said opening, friction shoes in wedge engagement with said member and in frictional engagement with respective columns, said shoes being entirely disposed beneath the upper level of said group, and a bolster supported from 35 said group and said shoes.

20. In a railway car truck, a side frame comprising spaced columns and an intervening bolster opening, resilient means on said frame in said opening, wedge means supported on said resilient means, friction elements engaging said wedge means and respective columns, a bolster in said opening comprising a bottom wall above said elements and bearing vertically thereon for actuation thereof, and a spring group on said frame bearing against said wall for support of said bolster.

21. In a railway car truck, a side frame comprising spaced columns and an intervening bolster opening, resilient means on said frame in said opening, a friction member thereon, friction shoes engaging said member and respective columns, a bolster in said opening comprising a substantially horizontal bottom wall above said shoes and bearing vertically thereon, and a spring group on said frame for support of said bolster.

22. In a railway car truck, a side frame comprising spaced columns and an intervening bolster opening, resilient means on said frame in said opening, a friction member on certain of said means, friction elements engaging said member and respective columns, and a bolster in said opening above said elements and comprising a substantially horizontal bottom wall supported from other of said means, and means engaging said bolster with said elements for actuation thereof, said elements being entirely disposed beneath said bottom wall.

23. In a railway car truck, a side frame comprising spaced columns and an intervening bolster opening, resilient means on said frame in said opening, a friction member on said means, friction elements in engagement with said member and respective columns, a bolster in said opening above said elements, rigid means between said

10 15 20 25 30 35 40 45 50 55 60 65 70 75

bolster and said elements for interlocking said bolster therewith, and a spring group on said frame for support of said bolster.

24. In a railway car truck, a side frame comprising spaced columns and an intervening bolster opening, springs on said frame in said opening, a friction member seated on one of said springs, friction elements in frictional engagement with said member and respective columns, and a bolster comprising a bottom wall supported on the other of said springs and operatively engaged with said elements, said elements being entirely disposed beneath said bottom wall.

25. In a railway car truck, a side frame comprising spaced columns and an intervening bolster opening, springs on said frame in said opening, a friction member seated on one of said springs, friction elements in frictional engagement with said member and respective columns, and a bolster supported on the other of said springs and operatively engaged with said elements, said operative engagement comprising a rigid member seated upon and engaged with said elements and also engaged with said friction member, and means engaging said bolster with said rigid member.

26. In a railway car truck, a side frame comprising spaced columns and an intervening bolster opening, a plurality of friction shoes engaged with respective columns, bolster supporting springs on said frame in said opening, a friction member on certain of said springs and comprising friction surfaces in engagement with said shoes, a follower member seated on and engaged with said shoes and engaged with said friction member, and a bolster end received in said opening, supported on other of said springs, and engaged with said follower member.

27. In a railway car truck, a side frame comprising spaced columns and an intervening bolster opening, a plurality of springs on said frame in said opening, a friction member on the intermediate of said springs, friction elements engaged with said member and respective columns, and a bolster supported on other of said springs and engaged with said friction elements.

28. In a railway car truck, a side frame comprising spaced columns and an intervening bolster opening, a plurality of springs on said frame in said opening, a friction member on certain of said springs, friction elements engaged with said member and respective columns, a follower member seated on and engaged with said elements and interlocked with said friction member, and a bolster supported on other of said springs and operatively engaged with said follower member.

29. In a railway car truck, a side frame comprising spaced columns and an intervening bolster opening, friction shoes in engagement with respective columns, a friction element resiliently supported from said frame in wedge engagement with said shoes, a bolster supporting spring group on said frame in said opening, a bolster comprising a substantially horizontal bottom wall supported on said group above said shoes, and actuating means engaging the bolster with said shoes.

30. In a railway car truck, a side frame comprising spaced columns and an intervening bolster opening, friction shoes in engagement with surfaces on respective columns extending transversely of said frame, means resiliently supporting said shoes from said frame, said means comprising a member in complementary wedge engagement with said shoes, a bolster supporting

spring group on said frame in said opening, a bolster comprising a substantially horizontal bottom wall supported on said group above said shoes, and actuating means engaging the bolster with said shoes, said actuating means comprising a member seated on the tops of said shoes.

31. In a railway car truck, a side frame comprising spaced columns and an intervening bolster opening, friction shoes in engagement with surfaces on respective columns extending transversely of said frame, means resiliently supporting said shoes from said frame, said means comprising a member in wedge engagement with said shoes, a bolster supporting spring group on said frame in said opening, a follower member seated upon and engaged with said shoes, and a bolster on said spring group and operatively engaged with said follower member, said shoes being entirely disposed beneath the upper level of said group.

32. In a railway car truck, a side frame, a spring group supported therefrom, a friction member resiliently supported from said frame centrally of said group, friction shoes at opposite

sides of said member in wedge engagement therewith, said shoes being entirely disposed beneath the upper level of said group and being in frictional engagement with friction means on said frame, and a bolster supported from said group and said shoes.

33. In a railway car truck, a side frame, a plurality of springs supported therefrom, a friction member on the intermediate of said springs, friction elements frictionally engaged with said member and with means on said frame, and a bolster supported on the other of said springs, said bolster being operatively associated with said friction elements.

34. In a railway car truck, a side frame comprising spaced columns and an intervening bolster opening, resilient means on said frame in said opening, a friction member on said resilient means, friction shoes engaging said member and respective columns, and a bolster in said opening comprising a substantially horizontal bottom wall above said shoes and bearing vertically thereon.

DAVID M. LIGHT.
